UNITED STATES PATENT OFFICE

ROBERT H. BLISS, OF EAST SYRACUSE, NEW YORK

METALLIC WINDOW CONSTRUCTION

Application filed September 8, 1928. Serial No. 304,659.

This invention relates to metallic window constructions, and more particularly to the construction of casement windows of the type adapted to provide access from within to both sides of the window in its open position, as for cleaning purposes.

It is a general object of the invention to simplify and improve the construction and operation of devices of this character.

Another object of the invention is to provide a construction of this character in which there are no projections outside of the confines of the window frame.

Still another object of the invention is to provide a means for automatically providing access to the outer side of the window as it is swung open.

A still further object of the invention is to provide an improved locking means for window construction which will also serve as a means for holding the window open.

Other objects and features of novelty will be apparent as the following description proceeds, as taken in connection with the accompanying drawings, in which:

Figure 1 is a diagrammatic view of a casement window to which my invention is applied;

Figure 2 is an enlarged view having parts broken away, and showing a vertical cross section through the window construction in the closed position;

Figure 3 is a horizontal cross section taken along the line 3—3 of Fig. 2;

Figure 4 is a vertical cross section taken along the line 4—4 of Fig. 2;

Figure 5 is a detail view of the locking device showing in dotted lines the position of the parts when the device serves as means for holding the window open;

Figure 6 is an enlarged view of the lower corner of the window construction such as shown in Fig. 4, but showing the sash in the open position; and

Figure 7 is an enlarged detail view similar to Fig. 3, but showing the sash in the open position.

Referring more particularly to the drawings, the window construction embodies essentially a frame 10 and a sash 11. The frame

10 may be of any desired construction, but in the preferred form of the invention shown in the drawings it is constructed of a rolled shape such as shown in Fig. 3, and comprising an angle having an inner flange 12 and a leg 13 which is provided with an inwardly directed flange 14 and two heel flanges 15 and 16.

The sash 11 comprises a rectangular frame constructed of a rolled shape somewhat similar to the frame shape, but inverted with respect thereto. The sash angle has a flange 18 adapted to overlie the flange 14, and a leg 19 having a heel flange 20 and an inwardly directed flange 21 which is adapted to overlie the outer portion of the frame flange 12. The sash may be glazed with a single pane, but in the form shown in the drawings, muntins 22 and rails 23 are provided for mounting a plurality of panes.

The frame 10 comprises side bars 25 and 26, an upper bar 27 and a lower bar 28. Correspondingly the sash 11 comprises stiles 30 and 31, and rails 32 and 33.

The sash is pivoted to the frame in such a manner that the pivot points may move toward the center of the opening as the sash is swung outwardly, and at the same time the sash may move radially with respect to the pivot so that the sash may take a position outside of the confines of the window frame. For this purpose slides 34 and 35 are respectively secured to the outer sides of the sash rails 32 and 33. These slide members are each provided with a pair of elongated openings 37 and 38, respectively receiving headed pins 40 and 41 secured to the rails between the flange 18 and the heel flange 21. This construction permits limited sliding movement of the sash and slides, the slide moving in the plane of the sash, and the sash moving radially with respect to its pivot. The pivot comprises pins 43 and 44 respectively adapted to fit an aperture in the end of the respective slides 34 and 35.

To permit the pins to move toward the center of the opening when the slide is swung outwardly, track members 45 and 46 are rigidly secured to the upper and lower frame members 27 and 28. These tracks lie snugly against the base 13, between the flanges 12 and 100

14 and comprise strips of sheet material of substantially channel shape, forming re-entrant flanges 50 and 51 respectively, which serve to retain a friction member 52, but 5 permit the pin itself to pass therebetween.

To automatically cause the sash to move radially with respect to the pivot, spring means is provided to bear against the pin, and in the present form a flat leaf spring 55 is 10 provided having its upper end secured to the stile 30 of the sash as by rivets 56 and 57 and having its lower free end 58 bearing against the upper end of the pin 43 which projects through the slide member 34.

15 Retaining means is provided to limit the swing of the sash about its pivots, such as the link 59, best shown in Fig. 7. One end of the link is pivoted on a stationary pin 53 carried by the lower frame member 28, and the other 20 end of the link is pivotally received by the pin 41, as shown in Figs. 6 and 7.

When the window is in the closed position the parts take the position shown in Fig. 2 with the hinges 43 and 44 and their friction 25 members 52 lying close against the inner frame member 25, and the spring 55 compressed between the pin 43 and the sash member 30. When the window is opened, the spring 58 bearing against the pin 43 will urge 30 the sash radially of the pivot, causing the pins 40 and 41 to occupy the far end of the slots 37 and 38. As shown in Fig. 7 this permits the flange 18 to ride outside of the confines of the window frame and prevents marring of the 35 finish and faulty operation. Then the stile 30 may be grasped and pulled bodily toward the center of the opening. This will cause the sash to pivot about the pin 41, supported by the link 59. Sufficient force must be exerted 40 to overcome the resistance of the friction member 52 to cause it to ride in the tracks 45 and 46 and permit the pin to take the position shown in Figs. 6 and 7.

With this arrangement an attendant may 45 stand inside the building and reach outward between the frame member 25 and the sash member 30 to clean the outside of the window. The inside of the window may be cleaned while it is in the closed position, or may of 50 course be cleaned while the parts are in the position shown in Figs. 6 and 7, access being provided between the frame member 26 and the sash member 30.

To lock the window in the closed position, 55 or to hold the window partly open for the purposes of ventilation, there has been provided a device such as shown in Fig. 5. This device comprises a flat plate 60 fastened to the flange 20 of the sash 19 and provided with a pivot pin 61. Pivoted on the pin 61 is a 60 clamping device having a lever arm 62 constituting a handle and a locking arm 63 having a cam surface 64 adapted to swing under a pad 65 carried by the flange 12 of the frame. 65 When the parts are in the position shown in

full lines in Fig. 5 this device serves to securely lock the parts together in the position shown with the flange 21 fitting against the frame flange 12 and the sash flange 18 overlying the frame flange 14.

When the window is opened and the handle 70 62 rotated approximately 180 degrees about the pin 61 to the position shown in dotted lines in Fig. 5, it constitutes means for holding the window partly open for purposes of ventilation. The handle 62 is provided with a hook 67 having an abutment surface 68 adapted to engage the frame flange 14. It will be obvious from an inspection of the structure shown in dotted lines in Fig. 5 that this arrangement 75 will serve to hold the sash partly open with respect to the frame and prevent accidental opening or closure thereof.

80 While the invention has been shown and described in great detail for the purpose of adequate disclosure, the broad idea of the invention is not to be limited to any of the details shown or described but includes such embodiments thereof as come within the scope 85 of the subjoined claims.

Having thus described the invention, what is claimed as new and desired to be secured by Letters Patent is:

1. A metal window construction comprising in combination a metal window frame 90 having an opening, a metal sash fitting said opening, means for pivotally supporting said sash from said frame, and means permitting said sash to move radially with respect to its pivot when swinging open.

2. A metal window construction, comprising in combination, a window frame, a sash, a member slidable in the plane of the frame and a member slidable in the plane of the sash, said members being pivoted together.

3. A metal window construction comprising in combination a window frame, a sash, a member slidable in the plane of the frame and a member slidable in the plane of the sash, said members being pivoted together, and means for causing said sash to move radially of the pivot point when the sash is swung open.

4. A metal window construction comprising in combination a window frame, a sash, a member slidable in the plane of the frame and a member slidable in the plane of the sash, said members being pivoted together, and means for causing said sash to move radially of the pivot point when the sash is swung open, and friction means for retarding the motion of the member movable in the plane of the frame.

5. A metal window construction comprising in combination a metal window frame having an opening, a metal sash fitting said opening and having an external flange adapted to overhang said frame on all sides, means slidable in said frame for pivotally supporting said sash from said frame, and

means permitting said sash to move radially with respect to its pivot when swung open, to permit said external flange to clear said frame when the pivot means slides in the frame.

5 6. A metal window construction comprising in combination a frame, a stationary track secured to said frame, a member slideable in said track and carrying a pivot pin, a sash, 10 a member having one end receiving said pivot pin, and its other end having longitudinal sliding engagement with said sash.

15 7. A metal window construction comprising in combination, a frame, a stationary track secured to said frame, a member slideable in said track and carrying a pivot pin, a sash, a member having one end receiving said pivot pin, and its other end having longitudinal sliding engagement with said sash, 20 and a friction shoe carried by said pivot member for retarding its movement in the track.

25 8. A metal window construction comprising in combination, a frame, a stationary track secured to said frame, a member slideable in said track and carrying a pivot pin, a sash, a member having one end receiving said pivot pin, and its other end having longitudinal sliding engagement with said sash, 30 and a spring carried by said sash for urging said sash to slide along its member away from said pivot pin.

35 9. A metal window construction comprising in combination, a frame, a stationary track secured to said frame, a member slideable in said track and carrying a pivot pin, a sash, a member having one end receiving said pivot pin, and its other end having longitudinal sliding engagement with said sash, 40 and a spring carried by said sash and engaging said pivot pin for urging said sash to slide along its member away from said pivot pin.

45 10. A metal window construction comprising a frame and a sash pivoted therein to swing outwardly about one edge of the sash, the pivots being arranged to move toward the center of the opening of said frame when the sash is swung open to permit access from within to both sides of the sash for cleaning purposes, said pivots always remaining within the confines of said frame, and means permitting the sash to slide radially with respect to its pivots to a position entirely outside the confines of the frame.

55 11. In a casement window, the combination with a metal window frame comprising a base and a pair of spaced flanges presenting unbroken continuous surfaces facing outwardly of the frame, of a metal sash comprising a base and a pair of spaced flanges presenting unbroken continuous surfaces facing inwardly of the frame, the corresponding flat surface on the frame and sash being adapted to contact when the sash is closed 60 to seal the frame opening, and means located

wholly within the confines of the frame in the closed position of the sash for supporting the sash to swing outwardly to a position intermediate the sides of the frame and spaced substantially therefrom to permit access to both faces of the sash for cleaning the same.

70 12. In a casement window, the combination with a metal window frame comprising a base and a pair of spaced flanges presenting unbroken continuous surfaces facing outwardly of the frame, of a metal sash comprising a base and a pair of spaced flanges presenting unbroken continuous surfaces facing inwardly of the frame, the corresponding flat surfaces on the frame and sash being adapted to contact when the sash is closed to seal the frame opening, and means located wholly within the confines of the frame in the closed position of the sash for supporting the sash to swing outwardly to a position intermediate the sides of the frame and spaced substantially therefrom to permit access to both faces of the sash for cleaning the same, and means secured to said sash and adapted for selective engagement with either of said spaced flanges on the frame to retain the sash in closed or partly opened position as desired.

75 13. In a casement window, the combination with a metal window frame comprising a base and a pair of spaced flanges presenting unbroken continuous surfaces facing outwardly of the frame, of a metal sash comprising a base and a pair of spaced flanges presenting unbroken continuous surfaces facing inwardly of the frame, the corresponding flat surfaces on the frame and sash being adapted to contact when the sash is closed to seal the frame opening, and means located wholly within the confines of the frame in the closed position of the sash for supporting the sash to swing outwardly to a position intermediate the sides of the frame and spaced substantially therefrom to permit access to both faces of the sash for cleaning the same, and means located wholly within the confines of the frame in the closed position of the sash for supporting the sash to swing outwardly to a position intermediate the sides of the frame and spaced substantially therefrom to permit access to both faces of the sash for cleaning the same, and means pivoted on said sash and adapted in one angular position thereof to engage with the inner of said spaced flanges on the frame to retain the sash in closed position, and adapted in another angular position thereof to engage with the outer of said spaced flanges on the frame to retain the sash in partly opened position.

80 14. In testimony whereof I hereunto affix my signature.

ROBERT H. BLISS.
